[57] CLAIM

The ornamental design for a case for laser disks, as shown and described.

DESCRIPTION

FIG. 1 is a top view of a case for laser disks showing my new design;

FIG. 2 is a bottom view thereof;

FIG. 3 is a front view thereof;

FIG. 4 is a rear view thereof;

FIG. 5 is a right side view thereof;

FIG. 6 is a left side view thereof; and,

FIG. 7 is a perspective view thereof.

FIG.1

FIG.2

FIG.3

FIG.4

FIG.5

FIG.6

FIG. 7
